UNITED STATES PATENT OFFICE.

ARTHUR B. CLUNIES, OF ROCHESTER, NEW YORK, ASSIGNOR TO THE SILL STOVE WORKS, OF SAME PLACE.

DESIGN FOR FIRE-BRICK.

SPECIFICATION forming part of Design No. 25,532, dated May 19, 1896.

Application filed April 20, 1896. Serial No. 588,387. Term of patent 14 years.

To all whom it may concern:

Be it known that I, ARTHUR B. CLUNIES, a citizen of the United States, residing at Rochester, in the county of Monroe and State of New York, have invented and produced a new and original Design for Fire-Bricks, of which the following is a specification, reference being had to the accompanying drawings, forming a part thereof.

In the drawings, Figure 1 is a perspective view of the fire-brick, showing my design; Fig. 2, a bottom plan view of the same; Fig. 3, a cross-sectional view, and Fig. 4 a perspective view showing the opposite end from that in Fig. 1.

The leading feature of my design consists of the shape and configuration of the brick, substantially as shown.

The brick is substantially rectangular in form, having one face, the rib A, provided with an abrupt shoulder A' on one side, while the other slopes down gradually into the plane

face A². The upper corner between the face A² and the top B is rounded, and the lower rear corner is cut away or chamfered at B'. (See Fig. 3.) One end of the brick is provided with a rectangular recess C, and the edge D at one side of the recess is formed at an angle to the front face A². The lower corner beneath the recess C is also cut away back to the end of the edge D. The other end of the brick from that described is cut away at the rear corner, the projecting edge curving at the top, as indicated by F, leaving the surface G in a lower plane than said extreme end. A recess H is formed in this end extending from the bottom, as shown.

I claim as my invention—

The design for fire-bricks substantially as shown and described.

ARTHUR B. CLUNIES.
